(No Model.)

S. C. McLANAHAN & W. F. KIRK.
ORE WASHER.

No. 445,430.

Patented Jan. 27, 1891.

UNITED STATES PATENT OFFICE.

SAMUEL C. McLANAHAN AND WILLIAM F. KIRK, OF HOLLIDAYSBURG,
PENNSYLVANIA.

ORE-WASHER.

SPECIFICATION forming part of Letters Patent No. 445,430, dated January 27, 1891.

Application filed November 5, 1890. Serial No. 370,424. (No model.)

To all whom it may concern:

Be it known that we, SAMUEL C. McLANAHAN and WILLIAM F. KIRK, of Hollidaysburg, in the county of Blair and State of Pennsylvania, have invented a new and useful Improvement in Ore-Washers, of which the following is a specification.

Our invention relates to ore-washers of that form in which one or more shafts provided with radial blades revolve in a box or tank, the ore being agitated and carried forward to the discharge end by said blades. It is very important in washers of this class that the height of the water in the washer-box be over the tops of the shafts at the end at which the material is fed into the washer, so that the earth and clay may the sooner be saturated with the water and the ore washed with greater speed and facility.

Our invention consists in the peculiar construction and arrangement of the journals, journal-bearings, and end plates of the washer-box, whereby the renewal of the bearing-surface when worn may be more easily effected; and it also consists in the special construction of a flanged journal or gudgeon, a sleeve for the end of the shaft, and stirring-blades attached to the said sleeve, as herein-after fully described.

Figure 1 is a side view of a stirrer-shaft mounted in bearings in the washer-box, which is shown in longitudinal section. Fig. 2 is an enlarged sectional view of the journal, the journal-bearing, and end plate. Fig. 3 is a cross-section through the line $x-x$ of Fig. 1, and Fig. 4 is a cross-section through line $y-y$ of Fig. 2.

A is the washer-box, in which the ore is fed to be washed. This box is deeper at one end than it is at the other, so as to permit one end of the revolving shaft B to be immersed in the water. This shaft is journaled in bearings in the washer-box in an inclined position to the horizontal, and is armed with a series of radial stirrer-blades B', set spirally, so as to agitate the ore in the water to thoroughly wash it and also feed it toward the discharge end of the box. The shaft B is in the nature of a heavy log of octagonal cross-section, the ends of which are received and firmly socketed in

corresponding octagonal sleeves C. These sleeves and the shaft need not be octagonal, but may be of any other shape in cross-section. The sleeves C are made of cast metal with a flange a, to which is bolted at the lower end of the shaft the flange d of a gudgeon D. The journal and bearing at the lower end of the shaft, being immersed beneath the water and being liable to rapid wear on account of the grit, is made in the following way: The gudgeon D is of octagonal cross-section, and has slipped over it a removable jacket or thimble E, the outer periphery of which is circular and somewhat tapering and which forms the journal of the shaft, turning rigidly with the gudgeon. The latter need not be of octagonal shape, but may be square, polygonal, or any other shape that causes the thimble E to turn with it.

F is the journal-box, which receives the journal E, both of which are made of steel or chilled castings. This journal-box is held in a bracket-frame G, bolted to the end plate H of the washer-box, and said journal-box is provided with a pipe b, leading into the bearing-surfaces, through which a stream of pure clean water is kept running to continually wash out from the bearing-surfaces any grit that may have a tendency to work into the same.

In the end plate H of the washer-box is formed an opening with flange e, which opening is larger than the journal-box F, so that the latter may be taken through said opening when it is to be removed. The opening in this end plate is closed by a cap-plate I, which is bolted to the flange e and is provided with a flange or cup-like projection c, which extends to and bears against the journal-box F, forming a back-stop or abutment for the same. Now, when the journal-bearing becomes worn from the gritty water and heavy service, it is not necessary to lift out the end of the heavy shaft B, but the latter is blocked up to hold it in place, and, the cap I being removed, the journal-box F and journal casing or thimble E may be conveniently removed through the opening in the end plate without disturbing or altering the position of the heavy stirrer-shaft.

In feeding the ore to the washer-box it is

deposited at the deeper end of the box when the shaft is immersed, and at this point the hardest work is to be performed by the stirrer-blades B'. Instead, therefore, of attaching the first set of blades to the shaft B itself, we bolt them to the metal sleeve C. This not only gives them a much firmer connection, but it enables us to start the stirring much closer to the end of the washer-box, thereby preventing so much dead material from packing or lying undisturbed against the receiving end of the washer. The same arrangement at the other end of the shaft accelerates the discharge of the washed ore and prevents the choking of the discharge-outlet, which has given much trouble heretofore.

Having thus described our invention, what we claim as new is—

1. The combination, with the revolving stirrer-shaft in an ore-washer, of an end plate having an opening through it opposite the journal of said shaft, a journal-box of smaller size than said opening, a support for the journal-box of said shaft, and an end cap for closing said opening, substantially as shown and described.
2. The combination of the stirrer-shaft hav-

ing gudgeon D with removable journal-thimble E, the journal-box F, the supporting-bracket G, the end plate H, with opening in 30 the same larger than the journal-box, and the closing-cap I, closing said opening and having flanges c abutting against the journal-box, substantially as shown and described.

3. The combination of the inclined water-box and the inclined stirrer-shaft of an ore-washer, a sleeve having the end of the shaft socketed therein and provided with a journal, as described, and a stirrer blade or blades bolted to the said sleeve, substantially as and 40 for the purpose described.

4. The combination of the inclined water-box and the inclined stirrer-shaft of an ore-washer, a sleeve C, having the end of the shaft socketed therein and provided with a flange 45 a; a gudgeon or journal having flange d, bolted to the flange of the sleeve, and a stirrer blade or blades bolted to said sleeve, substantially as shown and described.
